UNITED STATES PATENT OFFICE.

HOWARD R. SHROYER, OF PORTLAND, OREGON.

CLOTHES-HANGING ATTACHMENT FOR TRUNKS.

1,200,248.

Specification of Letters Patent.

Patented Oct. 3, 1916.

Application filed May 17, 1915. Serial No. 28,569.

To all whom it may concern:

Be it known that I, HOWARD R. SHROYER, a citizen of the United States of America, residing at Portland, in the county of

Multnomah and State of Oregon, have invented certain new and useful Improvements in Clothes-Hanging Attachments for Trunks, of which the following is a specification.

10 This invention relates to a clothes hanging attachment for trunks and is designed for use in any style or kind of trunk, suitcase, and the like, that is sufficiently large to receive the same, without the slightest 15 alteration or change in the trunk, suitcase, or the like.

The invention comprises a light frame preferably of metal hinged at one end to the wall of a trunk, preferably the end wall, 20 and having a suitable support at its other end from which clothes hangers may be suspended. The frame, because of its pivotal connection to the trunk, may be raised into vertical position thus permitting one 25 to readily place his clothes or remove them from the hangers without inconvenience, and after securing them to the attachment by suitable straps or other securing means the frame may be lowered into the trunk 30 where it preferably rests upon the bottom thereof. The frame and the clothes supported therefrom when lowered will lie below the ordinary cleats that support the well known tray, and when raised, the frame 35 is rigidly sustained in an upright position by suitable braces. When lowered the frame may be fastened to the bottom of the trunk by any suitable means such as straps which securely hold the attachment against 40 movement.

Another advantage possessed by this device is the ease with which it may be applied to any trunk without alteration in the trunk, and removed therefrom, leaving the 45 trunk in its original condition. All that is necessary to secure the attachment in place is to screw or bolt the frame hinges against an end wall of the trunk and fasten the braces and straps on the bottom of the same. 50 Thus rigged the attachment is ready for use, and when desired, the screws or bolts

may be withdrawn and the attachment removed from the trunk and stored or placed in another trunk.

The device is simple, light and being of 55 skeleton formation occupies little room in the trunk and holds one's clothes smoothly and securely in place and prevents them from being crushed and wrinkled as is the case when packed in the ordinary manner. 60

In the accompanying drawings: Figure 1 is a perspective view of an open trunk of well known construction provided with the improved clothes hanging attachment which is shown folded within the trunk, 65 the clothes hangers and follower being omitted for clearness of illustration. Fig. 2 is a vertical longitudinal sectional view of a trunk with the clothes hanging attachment raised to upright position, two 70 hangers and the follower being in position. Fig. 3 is a perspective view of the attachment removed from the trunk. Fig. 4 is a side view of the top of the attachment. Fig. 5 is a detail view showing the means for 75 fastening the clothes hanging attachment in elevated position. Fig. 6 is a plan view showing a modified form of the top of the clothes hanging attachment. Fig. 7 is a 80 longitudinal sectional view illustrating a modified form of mounting the attachment in a trunk. Figs. 8 and 9 are views showing other modified forms of mounting the attachment. Figs. 10 and 11 show a further modified form of my invention. 85

In the drawings the clothes hanging attachment comprises a frame preferably of light sheet metal formed of two main side bars 15 and 16 which may be arranged in parallel relation and spaced apart to enter 90 freely within a trunk, or like traveling convenience. These side bars 15 and 16 may be connected together as by cross bars 17. The main side bars 15 and 16 may be bent forwardly as at right angles near one of 95 their ends 18, 19 and pivotally connected each to a hinge or stationary member 20, said hinge members being designed for rigid connection to a trunk wall by any suitable means as by screws or bolts. The opposite 100 ends of the side bars may be secured, as by rivets to an overhanging supporting bar

21 which may be of substantially U shaped formation, the arms or forwardly projecting portions 22 of each bar being disposed substantially parallel to each other and to 5 the bent ends 18, 19 of the side bars and perpendicular to said side bars. The extremities 23 of the arms 22 may be turned inwardly toward each other, see Fig. 1, and project a short distance from the arms. 10 Braces 24 may be employed to firmly support the arms 22, said braces being secured to the side bars and the arms by rivets or any other suitable means.

The arms 22 are designed to support 15 clothes hangers 25 and a follower 26, each clothes hanger is shown as fastened to a bar 27 the ends of which rest on the arms 22 and are preferably notched as at 28 on the under edges to engage over the upper 20 edges of said arms and prevent the bar slipping therefrom but permitting the bar to have a sliding movement on said arms. It is obvious that in lieu of notches 28 suitable hooks or other expedients may be employed. The follower 26 which may be a 25 light open frame of wood or a solid strip of wood or other material is also suspended from the arms 22 by means of suitable suspension elements such as the hooks 29 secured to the upper ends of the follower and projecting laterally therefrom. The 30 hangers 25 and follower 26 are suspended from the arms in the manner described to permit easy removal or insertion in place 35 as the quantity of clothing demands, but to hold the hooked ends of these parts on the arms a suitable means is employed such as a strap 30 of any suitable material which is placed over the hooks or notched ends on 40 each side and fastened tightly to the bar 21 and the extremities 23 thus keeping the hangers and follower from slipping or being jarred out of place. A sheet of card 45 board, fiber, or other suitable tough, light material 31 is secured to the cross bar 17 between the side bars 15 and 16 by rivets or other suitable means and such sheet forms a support for the clothing when suspended from the hangers and when the attachment is lowered into the trunk. Straps 50 32 and 33 are passed through slots 34 in the side bars 15, 16 and are of sufficient length to be brought around the follower and fastened by buckles, thus preventing 55 any movement of the clothing supported by my improved attachment when being packed. My improved clothes hanging attachment may be held in position at the bottom of the trunk by straps 35 secured to the interior of the trunk in any suitable manner and which pass around the attachment when it is folded within the trunk. These straps 60 prevent the attachment moving on its pivots

when the trunk is in transit and is subject-
ed to incidental jars, blows, etc.

65

The bent ends 18 and 19 of the side bars 15 and 16 are preferably of such length that when the attachment is folded in the trunk A, as in dotted lines Fig. 2, it will rest on the bottom thereof and the hinged 70 members 20 will be below the tray cleat a. The arms 22 are preferably of such length that their ends 23 do not project above the adjacent tray cleat, the attachment thus offering no impediment or obstruction to 75 the usual tray with which trunks are generally provided.

70

When the clothes hanging attachment is raised into vertical position as in full lines Fig. 2, the hangers will be in convenient 80 position for placing clothes thereon or removal therefrom and when so raised it may be held in elevated position as by two braces 36 pivoted preferably to the bottom of the trunk, each brace being formed with 85 a longitudinal slot 37 having an offset 38 at one end that engages the pin 39 on the side bars and locks the attachment elevated. Upon disconnecting the off-sets from the 90 pin, the attachment may be folded into the trunk, the pins sliding readily in the slots 37.

80

In lieu of the U shaped supporting bar 21 with arms 22 and inturned ends 23 I may employ a rectangular frame 40 which 95 may be secured to the upper ends of the side bars as by rivets, see Fig. 6, to support the bars 27 of the coat hangers 25. If desired, bars 41 may be extended across the frame 40 and hangers 25 of well known design provided with wire hooks 42 may be suspended therefrom. In this form of my invention it is not necessary to have a specially formed coat hanger but a common well known hanger as above described, may 100 be employed.

100

Fig. 7 shows a modified means of mounting the clothes hanging attachment in the trunk and comprises a link 43 pivoted to each side bar 15^a a short distance from its 110 lower end, and to the trunk each side bar having a pin 44 projecting laterally from its lower end that slides in a slotted plate 45 fastened horizontally to the respective sides of the trunk near the bottom. When 115 the attachment is brought to upright position the pins 44 drop in offsets 46 from the slots in the plates 45 and lock the attachment immovable.

105

In Fig. 8 the bent ends 17^b of the side 120 bars 15^b are hinged to upright posts 47 fastened on the bottom of the trunk; while in Fig. 9 pins 48 hinge the side bars, 15^c directly to the sides of the trunk just below the plane of the tray cleats a. Hinged and 125 slotted braces 36, similar to those described,

125

engage pins 39 in the side bars of both forms and hold the attachment upright.

In the form shown in Figs. 10 and 11 I may employ a frame comprising a main member 60 which may be bent forwardly at its upper and lower ends to provide the extensions 61 and 62, the extension 62 being hinged to one end of the trunk near the upper end thereof but below the cleat *a*. Any suitable means may be employed to maintain the frame in an upright position but I have employed the supporting member 63 having outwardly turned ends 64 which are adapted for travel in suitable guideways 65 arranged along the sides of the trunk. The forward ends of these guideways 65 are provided with notches 66 in which the ends 64 may be seated to maintain the frame elevated. The supporting member 63 may be pivotally attached to the frame as by the bent strap 67. The coat hangers and the follower may be suspended from the upper extension 61 of the frame 60 as will be obvious, the free end of the extension being up-turned as at 68 to prevent the coat hangers, etc., from sliding off. The frame 61 is provided with upper and lower cross bars 69 and 70 to which the fiber board 31^a may be attached. Upper and lower straps 32^a and 33^a may be employed to hold the clothes and follower securely in position.

It will be seen that my clothes hanging attachment is simple and inexpensive and may be readily applied to any trunk suit case, or the like, sufficiently large to receive it and without change or alteration of said trunk or suit case. The clothes are held smoothly and immovably by the straps 32 and 33 between the follower 26 and the sheet 31 and when turned down into the trunk the attachment and clothes lie entirely below the tray cleats and out of the way of the tray. When elevated the braces 36 hold the attachment rigid with the garment hangers at such height as to be in convenient position for handling while standing erect and upon loosening the straps 32 and 33 the clothes will be suspended in natural position from the hangers 25 and free from pressure in any direction just as in any ordinary wardrobe.

Having thus described my invention what I claim is:

1. In a trunk having rigid side and end walls and provided with the usual tray supporting cleats, a clothes hanging frame pivotally mounted within the trunk at one end thereof below the tray supporting cleats and adapted to be raised upright with its lower end positioned within the trunk and adapted to be folded horizontally within the trunk, means for maintaining the frame in its elevated position and means for securing the frame in lowered position within the trunk.

2. A clothes hanging attachment comprising a frame including side bars that have their lower ends bent outward and provided with hinge members adapted to be fastened within any trunk or like clothes receptacle, a support rigidly attached to the opposite end of the frame and overhanging the same, a plurality of clothes hangers and a follower removably carried by said support, means for holding the attachment in elevated position above the trunk, and means for securing the same when folded thereinto.

3. A clothes hanging attachment comprising a frame formed with a pair of side bars bent at right angles at one end and fastened at its other end to a U shaped supporting bar, hinge members pivoted on the extremities of the bent ends adapted to be fastened within a trunk or the like, a locking brace adapted to be hinged at the bottom of the trunk and engage and hold said frame when elevated, a plurality of clothes hangers each secured to a bar having notched ends to engage and be sustained by said supporting bar, a follower also depending from said supporting bar, and means for retaining the follower and hangers on said bar.

4. A clothes hanging attachment comprising a rectangular frame formed with a pair of side bars bent at right angles at one end and fastened at its other end to a U shaped supporting bar having parallel side arms, hinge members pivoted on the extremities of the bent ends of the side bars adapted to be fastened within a trunk or the like and at one end, a slotted locking brace adapted to be hinged at the bottom of the trunk and engage by means of its slot a pin on the frame and hold said frame erect when the pin enters an offset from the slot, a plurality of clothes hangers sustained by the arms of said supporting bar, a follower also depending from said arms, and means for retaining the follower and hangers on the arms.

5. In combination with a trunk having tray supporting cleats, a frame adapted to be hingedly supported at one end within the trunk whereby it may be raised above the trunk and folded thereinto, hinge supports for said frame secured at one end of the trunk below the tray supporting cleats, means at the other end of the frame for supporting a plurality of coat hangers, the upper end of said means terminating short of the tray cleats when the frame is folded within the trunk, means for supporting the frame in elevated position and means for securing the frame within the trunk.

6. In combination with a trunk having tray supporting cleats and a tray supported thereon, a clothes hanging frame hinged at one end within the trunk and adapted to be

raised upright above the same and folded thereinto, the hinges for said frame being located at one end of the trunk below the cleats, means at the other end of the frame for supporting a plurality of coat hangers, said means being so constructed as to terminate short of the tray supporting cleats when the frame is folded within the trunk, and means

for supporting the frame in elevated position.

In testimony whereof I affix my signature in presence of two witnesses.

HOWARD R. SHROYER.
